BACKGUARD PANEL FOR COOKING STOVES

Richard E. Hitchcock, Birmingham, Mich., assignor to Sears, Roebuck and Co., Chicago, Ill., a corporation of New York

Application January 26, 1950, Serial No. 7,481

Term of patent 7 years

(Cl. D81—25)

To all whom it may concern:

Be it known that I, Richard E. Hitchcock, a citizen of the United States and a resident of Birmingham, in the county of Oakland and State of Michigan, have invented a new, original, and ornamental Design for a Backguard Panel for Cooking Stoves, of which the following is a specification, reference being had to the accompanying drawing, forming a part thereof.

Fig. 1 is a front elevation of a backguard panel for cooking stoves embodying my new design;

Fig. 2 is a top plan view thereof;

Fig. 3 is a transverse sectional view taken approximately on line 3—3 of Fig. 1;

Fig. 4 is a transverse sectional view taken approximately on line 4—4 of Fig. 1;

Fig. 5 is a transverse sectional view taken approximately on line 5—5 of Fig. 1; and

Fig. 6 is a transverse sectional view taken approximately on line 6—6 of Fig. 1.

I claim:

The ornamental design for a backguard panel for cooking stoves, as shown.

RICHARD E. HITCHCOCK.
